UNITED STATES PATENT OFFICE.

EDWARD D. CONKLIN, OF MADISON, NEW JERSEY, ASSIGNOR TO THE WHITEHEAD & HOAG COMPANY, OF NEWARK, NEW JERSEY, A CORPORATION OF NEW JERSEY.

TOP.

1,164,991.

Specification of Letters Patent. Patented Dec. 21, 1915.

Application filed August 7, 1915. Serial No. 44,213.

To all whom it may concern:

Be it known that I, EDWARD D. CONKLIN, a citizen of the United States, and resident of Madison, in the county of Morris, in the State of New Jersey, have invented new and useful Improvements in Tops, of which the following, taken in connection with the accompanying drawings, is a full, clear, and exact description.

10 This invention relates to certain improvements in tops.

The primary object of the invention is to produce a toy top of simple construction, readily manufactured, and which by reason 15 of its inexpensive nature constitutes not only an article of considerable commercial value, but also may efficiently be used by manufacturers as a gratuitous advertising medium for their products.

20 Other objects and advantages will appear from the following description, taken in connection with the accompanying drawings, in which—

Figure 1 is a perspective view of the top. 25 Fig. 2 is a vertical central cross section of the same. Fig. 3 is a view of the spindle or post.

The invention as shown comprises a suitable spindle or post —1— of metal or other 30 suitable material, said post preferably slightly tapered at the bottom.

Associated with the spindle and preferably integral therewith, as shown, is a suitable shoulder —2— having, in the structure 35 illustrated, a substantially flat upper face and a tapered or frusto-conical lower face.

A suitable disk —3— of cardboard or other suitable material adapted to carry advertising matter is mounted on the spindle 40 and engaged with the lower face of the shoulder —2—, said shoulder limiting the extent of upward movement of the disk along the spindle.

A suitable plate —4—, preferably, as 45 shown, a metallic circular plate, although other suitable material may be used, is also mounted on the spindle —1— and engaged with the flat upper face of the shoulder —2—, said shoulder limiting the downward 50 movement of said disk along the spindle.

It will now be readily apparent that if the disk and plate are secured together, they will constitute a compound flat member lying in a plane at substantially right angles to

the spindle —1—, and that such member 55 will be held from movement in either direction along the spindle by the shoulder —2—, and to accomplish this purpose in a preferred manner the edge of the metallic plate —4— is bent downwardly and perhaps 60 slightly inwardly to form a flange —5— confining the edge of the disk —3—, whereby the parts are rigidly connected.

Preferably the metallic plate —4— is provided with a layer or sheet —6— of celluloid, adapted to display advertising or artistic matter, and having its edge turned inwardly about the flange —5— and adapted to be positioned in the completed structure between the edge of the disk —3— and said flange. Details of this character may, however, be widely varied, and certain of the elements described as preferable changed or entirely omitted, without departing from the spirit of this invention as 75 set forth in the appended claims.

What I claim is:—

1. A top comprising a spindle having a shoulder associated therewith, a disk upon one side of the shoulder, a plate upon the 80 opposite side of said shoulder, and means connecting the disk and plate.

2. A top comprising a spindle having a shoulder associated therewith, a disk upon one side of the shoulder, a plate upon the 85 opposite side of said shoulder, a covering of celluloid or other material for said plate, and means connecting the disk and plate.

3. A top comprising a spindle having a shoulder associated therewith, a disk upon 90 one side of the shoulder, a plate upon the opposite side of the shoulder, said plate having portions flanged about the disk to rigidly connect the parts.

4. A top comprising a spindle having a 95 shoulder associated therewith, a disk upon one side of the shoulder, a plate upon the opposite side of the shoulder, a covering of celluloid or other material for the plate, said plate having portions flanged about the 100 disk to rigidly connect the parts.

In witness whereof I have hereunto set my hand this 30th day of July 1915.

EDWARD D. CONKLIN.
